UNITED STATES PATENT OFFICE

2,057,053

LOOM FOR WEAVING

Fernand Philly, Lyon, France

Application October 5, 1933, Serial No. 692,325
In France October 11, 1932

1 Claim. (Cl. 28—1)

The present invention relates to a loom for weaving, in which a loop is formed by one or several warp threads through which the weft thread is passed, the mesh fabric being obtained by twisting together the warp thread or threads and the weft thread.

Means for the manufacture of fabrics having these characteristics are described in my Patent No. 1,617,347, and a loom of this kind is described in my Patent No. 1,683,052.

The present invention has for its object improvements in looms of the type above defined, with the object of improving their operation and increasing their speed.

15 In the present looms, the starting and stopping of the loom are effected by hand by means of a rod or an operating lever, and the automatic means for stopping the loom in cases where the shuttle does not reach its box are mechanical, heavy and violent.

20 The picking of the shuttle is done by means of heavy hammers lifted by cams, they being released for their stroke by springs.

25 The work-bar put into movement by cams does not follow a rational path, which necessitates the speed being reduced, the bar being retained by springs in the direction of upward lift, and shock absorbers provided in the direction of descent.

30 In my prior Patent No. 1,683,052 the path made by the working bar for forming a loop is polygonal and the mechanism is positioned a relatively great distance from the yarn guide. Due to this arrangement during each cycle in the formation of a loop, the loom is subjected to jerks and shocks caused by the sudden changes in the direction of movement of the working bar. Also, by reason of the sudden changes of direction the warp threads are submitted to sudden thrusts and releases. This makes it necessary to operate the loom at a low 35 rate of speed—a most undesirable condition.

40 One of the objects of the present invention is to eliminate the above disadvantages and to construct a loom, of the character indicated, capable of operating at a greater speed.

45 Other aims and purposes are to provide—

(1) Means for guiding the work-bar, these means consisting in the combination of a fixed cam and a counter-cam or any other equivalent arrangement constructed in such manner as to cause a displacement, which is regular and without jerk or shock, of this bar around the thread-guides, which serves to form the loop, and to guide this bar until the mesh is finished.

(2) Means for guiding the weft threads, comprising a bobbin box having separate compart-

ments or divisions for the various bobbins of the weft threads and separate outlet passages for each of these threads.

(3) An electric-mechanical driving arrangement for the whole loom which permits the starting and stopping and as required a reversing movement. The automatic stopping being accomplished by the release of a safety device (shuttle feelers, thread feelers etc.), the loom being always stopped in the same position, and it being impossible to start operation again in the case of accidental stoppage of the loom until this accident has been repaired.

(4) A grooved cam for operating a reed bar without shock or jerk.

(5) Hammers for the picking of the shuttle carried by levers which may be balanced or not, operating with a rotary motion.

(6) A roller conical at its ends for stretching the selvages of the fabric made by the loom.

(7) A braking arrangement for the warp roller, this arrangement being mechanically controllable by friction or by a ratchet wheel.

(8) An operating and controlling arrangement for the takeup of the fabric and its tension, this arrangement being controllable by springs and a loose wheel having a pawl and toothed wheel.

The annexed drawings illustrate by way of example a loom in accordance with the invention:

Figure 1 is an elevation of the loom shown diagrammatically.

Figure 2 an end view from the side of the electromagnetic operating mechanism.

Figures 3, 4, 5, and 6 show the various positions occupied respectively by the work bar and its operation by the cam during the production of a mesh relative to the stationary thread-guides.

Figure 7 is an elevation of the thread-guide.

Figure 8 a sectional elevation of the box for the independent bobbins.

Figure 9 a plan view of the outlet channels.

Figure 10 an elevation of a shuttle.

Figure 11 is an end elevation of this shuttle.

Figure 12 a plan view of this shuttle.

Figure 13 the driving mechanism for the picking of the shuttle.

Figure 14 shows the shuttle feeler arrangement for the automatic stoppage of the loom.

Figure 15 shows the roller for tensioning the selvages.

Figure 16 shows the frictional braking of the warp roller.

Figure 17 shows the driving of the warp-roller by a ratchet wheel.

Figure 18 the automatic operating means for the fabric take-up roller.

Figure 19 is a diagram showing the mounting and connections of the remote-control and electromagnetic apparatus of the loom and its shuttle.

In these figures, the same reference figures indicate the same parts.

As shown in Figs. 1 and 2, the loom is composed essentially of a frame 1 mounted on a base 2. On the main shaft of the loom 3, driven by an electric motor 4, is mounted a grooved cam 5 which produces the rocking movement of a suitable lever 6 supporting the reed-bar 7 and which, whatever its speed may be, permits this bar to follow a given path without shock or jerk.

On this lever 6 and moving with it is fixed the supporting lever 8 of the work-bar 9 guided by a fixed cam 10 having a slot or path 10' in which is guided a pin 10'' arranged on the said lever 8.

On the main shaft 3 is mounted a cam 11 having ratchet teeth with two oppositely situated dogs or pawls 12, 13 which can come in contact with the cam 11 and arrest it by means of teeth whenever that is necessary.

One of these pawls 12 is in constant contact with the cam. The other pawl 13 held back during normal working by the electric locking device 15, is suitably disposed in the electric circuit of the loom-operating mechanism. The electric circuit being the same as that described in my U. S. application Ser. No. 680,321.

On the other hand, safety devices are provided, such as the shuttle feelers 24 and 25, or weft or warp thread feelers, fabric tension feelers, and the like.

On the frame is mounted a roller 26 on which the warp threads 27 are wound which pass through the holes 28, 29, 30 of the tread-guide 31 to form the loop 32 (Fig. 7).

The passage or opening 33 in the needle or guide 31 permits the passage of the shuttle, while the inclined part 34 allows the passage of the weft thread 35 into the horizontal slot 36 which serves for guiding the weft tread until the complete formation of the mesh.

As the mesh is finished, the fabric 37 which is guided at first by the roller 38 (Fig. 2), is wound up on the fabric or cloth-roller 39.

In its rotary movement the main shaft 3 drives the grooved cam 5 and the reed-bar 7, whilst the supporting lever 8 owing to the shape of guide slot 10' of the cam 10 gives at all times to the work-bar 9 the exact movement so that the warp threads and the fabric supported by the support may have the desired movement around the back of the needles or thread-guides. This movement might also be obtained by a very short connecting-rod suitably fixed to a stationary plate to replace that which the cam 10 carries.

In the position shown in Fig. 3, the work-bar 9 is raised by this movement, the weft thread is caught by the hook 46 of the shuttle (Fig. 12) and is picked through the openings 33 of the thread guides 31.

In Figure 4 the loop commences to close to form the mesh.

The mesh is formed, Figure 5, and the end of the reed-bar bears against the row of meshes which has just been formed, in order to push it against the preceding row of meshes of the fabric.

The position of Fig. 6 corresponds to the fall of the row of meshes which emerges from the

needles or guides to definitely take its place in the fabric.

The driving movement of the main shaft containing the work-bar 9 returns backward at the same time as the reed-bar 7. The warp threads 5 being no longer wound about the weft thread only oscillate around the last hole 30 (Fig. 7) of the needle 31 and resume a position at the rear for the formation of the loop. Finally, the work-bar re-occupies the upper position, Figure 4, ready 10 to form a new row of loops.

Because of the character of the cam slot 10' the work-bar is guided regularly and without jerk whatever its speed may be so that it produces neither slackness nor tension nor friction of the 15 threads and the fabric and it thus permits all of the loops to be made with a regular tension.

The weft threads in any number necessary for the formation of the mesh, are supplied by vertical bobbins 41 (Figure 8) arranged at the 20 bottom of a bobbin box 42 mounted or not on the base of the loom at a suitable place. The section at the place where the bobbins rest in the box being a little more reduced so that the thread which is drawn towards a hole 43 placed at the 25 upper part may in all circumstances unwind without friction or breaking along the walls of the box 42 which surrounds it.

After its passage through the hole 43 in the upper part, the thread is guided in a passage 44 30 specially provided with spring or rubber weft-stretching devices 45 (Figure 9) controllable by a tension device and thus led to the weft drawing devices which have for their purpose, with the aid of a Jacquard or any other equivalent arrangement, to present a suitable thread at the desired moment to the shuttle 19 so as to be drawn by the latter through the series of warp loops previously formed by the needles or thread-guides.

When it is desired to make fabrics without a Jacquard or like means, that is to say, with a single thread at the right and a single thread at left, which may be the same or different, it is not possible to do it with the shuttle as it has hitherto been made, no apparatus being provided to make the weft-drawing devices function, each of the weft threads must remain stationary and is forcibly moved in a reverse direction when the shuttle after having taken the weft on one side returns 50 on the other side.

To remedy this defect, the shuttle may be given a special form, Figures 10, 11, and 12; its ends are in the form of a whistle as shown in Fig. 10, so that the shuttle can avoid the weft threads 55 and push them aside without drawing them or hooking them at the moment when, at the end of its travel, it enters its box on any one side of the loom and definitely causes them to be placed in such manner that they are engaged in front of its hook 46 to be caught by the latter on the movement of the shuttle. The use of a shuttle of special form having ends in the shape of a whistle as shown in Fig. 10 and hook or other form, or of any similar arrangement, such as the employment of a shuttle without a hook and carrying its thread in itself by means of a cap or bobbin or the like, enables one to work with a weft at left and a weft at right alternately, or a weft at left or one at right only if the shuttle makes one of its picks empty without carrying the weft thread, without a Jacquard or cam or any apparatus to give it an empty movement which simplifies the working of the loom.

The rapid to and fro movement of the shuttle 75

19 is advantageously effected by two rotary shuttle-picking hammers or stickers 47 facing each other (Fig. 13), balanced or not, and operated with a sufficiently rapid rotary movement.

5 These hammers are for instance driven by the shaft 48 of special electric motors 17, 18, with a maximum starting torque so as to give instantaneously the maximum force and speed so as to have the greatest possible picking strength.

10 At the end of their travel they may be pulled back by a spring or any other suitable means.

The striking surfaces of the hammers or stickers are so constructed and treated that their stroke is exceedingly clean. According to requirements (when using a weft which is coarse or fine, rough or smooth), the speed of rotation may be varied by suitable means so as to regulate the violence of the blow, for instance, by varying the length of stroke of the hammer, its effective 20 mass, or its balancing, by interrupting the current before the end of the stroke of the hammer, and so on.

A mechanical device for reducing the speed to half relative to the number of revolutions of the 25 loom or an alternating keyed distributor 16, or any other electrical combination suitably driven by the main shaft of the loom, enables one or other of the motors 17, 18 for the picking of the shuttle being switched on at the desired time.

30 A remote-control mechanical and electro-magneto driving arrangement enables the loom to be put in forward or backward motion or stopped, as required, by simply operating push-buttons such as 21, 22, 24. To put the loom in backward motion and to stop it automatically by the release of a safety device, shuttle feelers, thread feelers, fabric, tension feelers or the like are provided. Whenever an accident in working occurs, such as the shuttle not entering its box, the 40 breakage of a warp or weft-thread, defective tension of the fabric etc., the arrangement is such that the stopped loom, whether the stoppage was intentional or automatic, always automatically takes the working position, and if it has 45 been stopped when it was normally working it is ready to start afresh; but it cannot restart on the other hand if the loom has stopped by reason of an anomaly in working whether it is driven by a motor or by hand—until this accident has 50 been repaired. This arrangement is fully described in my U. S. application Ser. No. 680,320.

The shuttle feeler levers for breaking the contact (Figure 14) comprise a rocking lever 49 which bears on the shuttle 19 when this latter 55 is in its box and establishes by a roller 50, which comes to bear on a contact-breaking lever 51 that oscillates about its axis, a contact 52 on the terminal 53. When the shuttle is not in its box, the breaking of the contact takes place at the 60 terminal 53 and the reversing cut-out driving the electric motor of the loom is then disconnected.

On the starting of the shuttle 19 and during the time corresponding to the normal duration of its travel from one side of the loom to the other, 65 two levers arms 56, suitably adjusted and mounted for example on the reed-bar, come to bear on the shuttle feelers 49 and prevent the current being interrupted during this time.

An arrangement having interposed springs 70 (55), or any other similar arrangement, may permit, if it is thought useful, contact to be made at the terminal (54) at the end of the travel to put the motor in backward rotation which at first brakes the looms carried along by 75 its own momentum. This reversing drive is sup-

plementary to the drive by the contact-maker for reversing 70 indicated further on and is connected in parallel with it. It is interrupted automatically by the toothed cam 11 (Fig. 2) mounted on the main shaft 3, which has two pawls 12 and 13, one of which 12, serves to limit the travel of the loom in a backward direction and bears normally on the cam 11, whilst the other 13 suitably arranged in the electric circuit, is normally held back by the electro-magnet locking 10 device 15, is liberated on the other hand by this electro-magnet in case of the release of one of the safety devices and engages with a tooth 69 of suitable form causing the backward motion by 15 a contact 70.

The motor rotates backwards, braking the vis viva of the loom which in its turn also rotates backwards. The cam 11 then throws off the pawl 13 and interrupts the current for rearward motion which had been switched on when the pawl 20 commenced to engage in the tooth 69.

Finally, the loom is stopped automatically in a desired position, as a rule, the starting position with its rotation in the normal direction, starting being only accomplished if the loom is 25 stopped owing to an accident in working whether it be operated by the motor or by hand, if this accident has been repaired.

Figure 19 shows the electrical diagram of the 30 whole operating mechanisms of the shuttle and loom such as have been hereinbefore described.

Certain fabrics, particularly light fabrics, may give rise to detrimental slackness in the selvedges 35 by reason of the great ease with which the fabric may be pulled at its edges. To remedy this drawback a special apparatus for stretching or tensioning the selvedges (Figure 15) may be introduced after the passage of the fabric over the work-bar 8. This apparatus being formed, for instance by a roller 38 of small diameter and of a length slightly less than the width of the fabric and terminating at the edges in parts which are slightly conical with the greatest diameter being 40 towards the outside. The total length of this apparatus will of course be at least equal to the 45 width of the fabric.

In passing over this roller the selvedges will be 50 pulled with a circumferential speed which is greater than that of the other parts of the fabric on the cylindrical part. Owing to this, the selvedges will undergo an additional stretching which is intended to remedy the slackness in the 55 selvedges referred to.

This roller will be normally drawn by the fabric 60 which is applied to its cylindrical part and wound automatically by the cloth roller 39, but this roller might be driven by a suitable special mechanism.

In order that the fabric may adhere better to the roller 38, the latter may be provided with grooves or covered with felt, canvas or emery powder glued on, or any other material or means which facilitates the adhesion that it is desired 65 to obtain for the traction of the fabric.

The warp roller 26 is braked in the usual manner (Fig. 16) by a friction strap 57 the tension of which can be regulated by a spring 58 or driven by a special mechanical arrangement having a 70 ratchet wheel 59, for example, (Fig. 17) combined in such a way that one or several teeth may be operated according to the design to be obtained. This arrangement is operated by a Jacquard or by any other equivalent system. The spacing of 75 the weft threads, which is done without any kind

of difficulty in a regular or irregular fashion, enables open-work fabrics in the style of lace to be manufactured, alone or combined with fabrics not of openwork. These fabrics may be provided for 5 the insertion of trimmings, ribbons, lacings or the like, or simply for embroidering within or to separate, by a suitable spacing of the weft threads at a given place, the fabrics or the articles manufactured in a more convenient manner and for 10 an exactly calculated number of weft threads, or finally to separate the fabrics to such an extent that by cutting fringes can be made.

At the lower part of the loom the take-up roller 15 38 for the fabric is operated at a speed which is a function of the length which has just been made, 15 a length which is substantially variable according to the closeness or the openness of the fabric.

The suitable winding tension of the fabric may be obtained (Fig. 18) by means of a spring arrangement 60, pulled by an arm 61 fixed to the reed-bar 6 and the amplitude of which will vary according to the point of attachment 62 of the controllable spring on this arm. The strength of pull of this spring 60 is partly counter-balanced 25 by an opposing spring 63 fixed on one hand to the frame of the loom and on the other hand to a part 64, which terminates the first spring 60 fixed to a loose wheel 65 mounted on the shaft 66 of the take-up roller.

30 This loose wheel 65 will then be operated with an alternative arrangement more or less great according as the lower spring 62 is as strong as or weaker than that of the upper one.

At the upper part of this loose wheel 65 is 35 mounted a pawl 67 which has for its object to operate on a toothed wheel 68 fixed on the take-up roller 38 and in its movement to draw the fabric to be wound more or less according to the tension of the latter.

40 A stop pawl or dog 71 fixed to the support of the roller or to the frame of the loom prevents

the roller 38 from turning backwards and the fabric from unrolling.

In order to be able to vary the winding strength it suffices to select the springs, especially the lower one 63, and to suitably adjust on the arm 5 61 the point of attachment 62 of the upper spring 60.

Thus the fabric-roller, driven in an automatic manner, takes up the fabric as it is made and at the same time gives it the necessary tension according to whether it is a thick or a light fabric, or whether it is a question of contracting, in a regular or irregular manner, the convolutions made on the loom.

Having now particularly described and ascertained the nature of my said invention and in what manner the same is to be performed, I declare that what I claim is:—

In a loom, in combination with a main frame, stationary yarn guides secured thereto to hold warp threads in the form of closed loops, means to insert weft threads through the loops to bind the warp threads together, a lever pivotally mounted upon said frame, a drive shaft, a cam carried by said drive shaft, means for operatively connecting said cam to said lever whereby pivoting movement in a positive manner will be transmitted to said lever, reeds secured to said lever and movable therewith between the adjacent yarn guides to draw loops off the latter onto the enclosed weft threads, a work bar pivotally connected to said lever, a second cam for guiding the work bar, a stud engaged in the said cam and carried by the frame of the loom and said second cam carried by the lever of the reed bar and the shape 35 of the latter cam being such as to ensure the guiding of the work bar around the yarn guides while permitting the formation and the guiding of the loops until the meshes are finished.

FERNAND PHILY.
